Primary Examiner — Kelley Donnelly(74) *Attorney, Agent, or Firm* — Ryan Kromholz & Manion, S.C.**CLAIM**

The ornamental design for a shelving unit, as shown and described.

DESCRIPTION

FIG. 1 is a front perspective view of an embodiment of the shelving unit;

FIG. 2 is a front perspective view thereof and showing items in place in dotted line;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines are for the purpose of illustrating the environment of the article only and form no part of the claimed design.
